SNOW SLIDE PREVENTER

Horace H. Royall, Bell, Calif.

Application July 2, 1936, Serial No. 88,655
Renewed February 17, 1938

1 Claim. (Cl. 256—1)

This invention relates to a means and method whereby snow slides especially from mountains or high elevations may be eliminated, in order to avoid the damage caused thereby to roads and traffic.

It is also aimed to provide a novel means and method of a permanent nature, which is sufficiently strong and braced to withstand the tremendous impact of snow slides.

10 The more specific objects and advantages will become apparent from a consideration of the description following taken in connection with the accompanying drawing illustrating an operative embodiment.

15 In said drawing:

Figure 1 is a view in elevation, showing my improvement diagrammatically as applied to a mountain;

20 Figure 2 is a side elevation showing the improvement applied to a mountain;

Figure 3 is a side elevation of the invention;

Figure 4 is a plan view of the invention;

Figure 5 is a vertical sectional view taken on the plane of line 5—5 of Figure 4, and

25 Figure 6 is a detail sectional view taken on the line 6—6 of Figure 5.

Referring specifically to the drawing wherein like reference characters designate like or similar parts, a mountain or incline is suggested at 30 10. At any desired location thereon, posts 11 are set into the ground. Such posts may be of wood, suitably treated to prevent undue decay and they may also be of metal. Obviously the posts may be of any desired size or shape. The posts are arranged in any desired manner and wire netting 12, employed in sheet form, is fastened at its terminals to adjacent posts by wrapping the same therearound as at 13 and nailing or otherwise securing the same thereto at 14, such wire

netting being fastened to intermediate posts if desired by the nails 14, by clamps or in any other desired manner. The netting 12 may be of large mesh or small mesh and of any size preferred and of any metal, sufficiently strong.

5 In addition, the earth is roughened intermediate the posts 11 as by the provision of trenches 15.

In addition, strong metallic bracing means are provided as at 16 and for instance, in the form 10 of wire having its terminals surrounding two of the posts, one at the top and the other at the bottom, and between the post being twisted or otherwise secured together as shown at 17, such element 16 being inclined and constituting effective braces.

15 It will be realized that the wire netting 12 may be arranged in any desired manner, crisscrossed or otherwise, so as to intercept any snow slides in order to arrest the same, aided by the trenches 20 15 which may be engaged by the slide and serve to check the momentum thereof and relieve adjacent posts of the impact.

The invention is a very sturdy and strong construction and is primarily adapted to remain permanently in place on the mountain or incline.

25 Various changes may be resorted to provided they fall within the spirit and scope of the invention.

I claim as my invention:—

30 A snow slide preventing means comprising posts, wire netting secured to the posts, posts behind the first mentioned posts, wire netting secured to the second mentioned posts, and brace means between and at an angle to the nettings extending 35 from the tops of certain of the first mentioned posts to certain of the second mentioned posts, adjacent the ground line.

HORACE H. ROYALL.
